ALLSTEELEQUIP COMPANY, OF AURORA, ILLINOIS, A CORPORATION OF ILLINOIS.

LATCH AND LOCK.

1,387,643.

Specification of Letters Patent. Patented Aug. 16, 1921.

Application filed November 5, 1919. Serial No. 335,838.

To all whom it may concern:

Be it known that we, AXEL F. ERICKSON and DANIEL W. SHIEK, citizens of the United States, residing at Aurora, in the county of

5 Kane and State of Illinois, have invented a new and useful Improvement in Latches and Locks, of which the following is a full, clear, and exact description.

This invention relates to latches or locks 10 for doors and other structures. More particularly, this structure is designed for use in connection with lockers for the storage of clothing or wearing apparel, and is especially designed to hold the mechanism in 15 position for re-latching when the door is open and to secure the re-latching thereof through the simple closing of the door.

The principal object of this invention is 20 the provision of a latch and lock, the former whereof will be actuated to engage the striker or jamb-plate and be latched without having to raise the operating mechanism, and thereby insure the latching operation whether the door is slammed or closed in an 25 easy manner. Other objects of the invention consist in the provision of a latch for doors and the like that is simple in construction and which may be stamped entirely of metal so that it is easy to manufacture and simple 30 in construction and can be sold for a reasonable price, or will not add materially to the cost of the structure with which it is assembled. The design of this structure facilitates the locking thereof through the instrumentality of a cabinet lock or padlock 35 or both where such double precaution may seem desirable. Also, by the provision of the specially designed striker or jamb-plate, the door after being latched is prevented 40 from being forced open by inserting a jimmy or similar tool between the edges of the doorway and the door, because the striker or jamb-plate coacts with the latch elements carried by the door in such manner that the 45 door may not be pulled outwardly nor forced laterally or sidewise to escape the jamb-plate. The foregoing objects and others are accomplished by substantially the means hereinafter fully described, and as 50 more particularly pointed out in the claims. Reference will now be had to the accompanying drawings forming a part of this specification, in which—

Figure 1 is a horizontal section of adjacent portions of a door and door-frame of

a locker showing the improved construction in plan in operative position, the view being taken on line 1—1, Fig. 2.

Fig. 2 is an elevation of the latching mechanism in the center of the structure, the view being taken on line 2—2, Fig. 1.

Fig. 3 is a view similar to Fig. 2 showing the mechanism raised in unlatched position and about to engage the striker or jamb-plate.

Fig. 4 is a vertical elevation of the mechanism looking at the same from the rear or back of the door.

Fig. 5 is a perspective of the latch supporting spring element.

In the drawings, similar reference characters are employed to designate the same parts throughout the divers views, and by reference to Fig. 1, the numeral 10 designates the upright angle-piece forming one edge of the door opening, and a portion of the frame of the locker, which latter is constructed in this instance, of metal sheets supported upon a frame-work of angle strips, similar to that just referred to. 75 Mounted upon this angle strip 10 are strikers or jamb-plates 11, the one about midway the height of the opening of the door being alone illustrated in Figs. 1, 2 and 3. The outer portion of the plates are offset or bent 80 obliquely inwardly to accommodate the thickness of the door and some of the mechanism carried thereby, as shown in Fig. 1, and provided with recesses or notches 12 for the reception of the latch clips. 90

The door, preferably, comprises a sheet of metal 13, the vertical edges whereof are folded or bent back upon themselves to provide rounded corners 14, and are folded flat against the rear face, as shown at 15 in Fig. 95 1. A slight distance from edge 14 the folded back portion is formed semi-circular to provide a reinforcing rib 16 on the back of the door, and the end edge 17 of this bent back portion is then folded flat against plate 100 13, all as shown in detail in Fig. 1.

There are, preferably, three strikers or jamb-plates 11; one midway the height of the door, as before mentioned, and one each adjacent the upper and lower ends of the 105 door, each of said strikers being adapted to be engaged by a latch clip of the special construction, herein shown. These latch clips, as seen in the drawings, are, preferably, of channel shape, the flange 18 where- 110

of is secured to a vertical reciprocable bar 19 and the web of the bottom of the channel being partially separated from the flanges to provide a downwardly extending tongue 20 adapted to seat in a pocket in the door, as hereinafter described. The flange 21 opposite flange 18 is shorter than the same and is constructed somewhat hook-shape to engage the striker or jamb-plate, and has its lower edge 22 inclined in the manner of a latch bolt or like structure. The folded back portion 15 of the door plate is, preferably, horizontally slitted, and the metal between these slits is punched outwardly to provide a strap 23 between which tongue 20 is adapted to be slidably mounted. It will now be seen that by raising bar 19 the three latches may be disengaged from the strikers or jamb-plate 11 and the door opened. For convenience, slots 24 are made in the door frame, and lateral members 25 on the upper and lower portions of a handle 26 are passed through said slots and secured to bar 19. Handle 26 is placed in a loop, as shown, and by grasping handle 26 and raising the same the latches may be disengaged, and both the upper and lower horizontal members of handle 26 are provided with extensions 25^a which are for the purpose of covering or obscuring slots 24 in the door through which the handle extends when the mechanism is in its lower or latched position.

As previously stated, the principal object 35 of this invention is to provide means for easily closing the door and insuring the latching of the same, and this is done by providing means for automatically engaging and supporting the latch clips with the bar and their associated elements in an elevated position when the door is opened, which means is adapted to release the clips and associated elements by engagement with the jamb-plate or other element. This consists in providing a spring plate 27, the lower end whereof is mounted upon the rear of the door by means of a pocket formed by a strap 28, similar to strap 23, heretofore mentioned, and above this strap the spring plate 27 normally extends away from the rear surface of the door. The spring plate is deflected or bent slightly to a different plane, at 29, for the purpose of causing it to engage the lower portion of flange 18; also to accommodate tongue 20 when the latter is in its lowered or latched position, as seen in Fig. 2, where the upper portion extends up into a slot α made in the corner of the lock clip between the members 18 and 21 thereof. A lateral member 30 projects to one side adjacent the upper end of spring 27, and this member is also bent laterally so as to press against the adjacent edge or plate 18 in slot α , as shown in Figs. 1 and 2.

65 When bar 19 is raised by moving handle 26

to the upper limit of its movement the offset extension 30 of the spring will be positioned slightly below the lower edge of member 18 and will snap under the same when the door is slightly opened, as shown in Fig. 3 of 70 the drawings, in which position it will support the latch clip in a position above the horizontal plane of the jamb-plate or striker 11. The portion of the spring above offset 29 is so positioned that it will be engaged 75 by the front face of the striker or jamb-plate when the door has been nearly closed, and a very slight contact made between these parts will press the upper portion of the spring toward the door and release offset 80 extension 30 from the under edge of member 18, thus permitting the latch clips and bar 19 to gravitate with their associated elements and cause flange 21 of the clip to pass over the striker or jamb-plate and engage 85 the opposite face thereof to latch the door.

When it is desired to employ a padlock for locking the door, we have provided a right angular projection 31 on the spring plate 27 that passes through a slot 32 in the 90 door plate and is provided with an aperture 33 alining with a corresponding aperture 34 in the lower member of the handle when the latter is in lowermost position (Fig. 2). The bale of a suitable padlock 35 is adapted 95 to be passed through these alining apertures 33 and 34 and locked, thus preventing the raising of handle 26 and the unlatching of the door.

There is, preferably, but one of these 100 springs 27 employed in this structure, and this is positioned at the intermediate latch clip. It is desirable to sometimes employ a cabinet lock upon the interior of the door, and for this purpose we bolt such a lock 36 105 upon the door panel in the manner shown in Fig. 1, and provide a lateral extension 37 upon the upper edge of the intermediate latch clip that extends obliquely from the inner edge of bar 19 forwardly toward lock 110 36 and is then provided with a forwardly bent end 39 that extends the same under the retractable bolt 38 of the lock to maintain the mechanism in its lowermost or latched position until bolt 38 is withdrawn through 115 the operation of the lock in the usual manner.

What we claim as new is:—

1. A latch for doors and the like comprising a longitudinally movable latch clip, a 12 jamb-plate adapted to be engaged thereby when in latched position, means for moving said clip, and a spring element adapted to engage said clip when the latter is out of latched position and to be disengaged therefrom through contact with said jamb-plate, said spring element provided with an extension 13 projecting through the door and adapted to be locked to the means for moving said clip.

2. A latch for doors and the like comprising

ing a latch clip, a jamb-plate adapted to be engaged thereby when in latched position, a vertically reciprocable rod to which the latch clip is secured, means for reciprocating said rod, and a spring element adapted to engage said clip when the latter is raised and to be disengaged therefrom through contact with said jamb-plate, said spring element provided with an extension projecting through the door and adapted to be locked to the means for elevating said rod.

3. A latch mechanism for doors and the like comprising a movable latch clip, a jamb-plate adapted to be engaged thereby when door is in closed position, means for moving said clip, and an element arranged to engage said clip when the latter is out of engagement with said jamb-plate, and to release the clip when said element is in contact with the jamb-plate; said means provided with an extension projecting through the door adapted to be locked to the means for moving said clip.

4. A latch for doors and the like comprising a movable latch clip having a hook-shaped latching portion, a jamb-plate adapted to be engaged by the hooked portion of said clip, means for moving said clip, and an element adapted to maintain the clip out of latched position and to be disengaged and permit the latching of said clip when said element contacts said jamb-plate.

5. A latch for doors and the like comprising a movable latch clip having a hook-shaped latching portion, a jamb-plate extending into the path of swing of the door and providing a stop to limit the closure thereof; said jamb-plate being adapted to be engaged by the hooked portion of said clip, means for moving said clip, and an element adapted to maintain said clip out of latched position and to be disengaged and permit the latching of said clip when said element contacts said jamb-plate.

45 6. A latch for doors and the like comprising a latch clip having a hooked latching portion, a jamb-plate adapted to be engaged by the hooked portion of said clip, a vertically movable rod to which the latch clip is

secured, means for elevating said rod, and an element adapted to maintain said rod in elevated position whereby said clip is retained out of latched position and said rod is lowered upon the contact of said element with the jamb-plate to return said clip to latched position.

7. A structure to be latched comprising walls forming a compartment open at its front, a door closing said opening consisting of a plate the horizontal edges whereof are folded back and provided with longitudinal beads intermediate the edges of the folded back portions, embossed straps formed in the folded back portions adjacent said beads forming suitable pockets, latch clips mounted to reciprocate in said pockets, jamb-plates on the compartment wall adjacent the door adapted to be engaged by said clips, and means for actuating said clips to disengage them from said jamb-plates simultaneously.

8. A device of the kind described comprising a wall having an opening, a door closing said opening, a vertically movable latch clip, a jamb-plate provided with a recess with which said clip coacts whereby said plate retains said clip against transverse movement in divers directions, and means for actuating said clip to disengage it from the jamb-plate.

9. A latch for doors and the like comprising a bar vertically reciprocable upon the door, a latch clip mounted on said bar, a handle secured to and projecting through the door for moving said bar, a jamb-plate with which said clip coacts when the door is latched, a spring element for maintaining said clip in unlatched position, and a member projecting from said spring element through the door and adapted to be locked to said handle.

Signed at Aurora, county of Kane and State of Illinois, this first day of August, 1919.
